UNITED STATES PATENT OFFICE.

GUSTAV ADOLF HECKERT, OF MUNICH, GERMANY.

GAS-RETORT.

No. 843,811.

Specification of Letters Patent.

Patented Feb. 12, 1907.

Application filed December 4, 1905. Serial No. 290,132.

To all whom it may concern:

Be it known that I, GUSTAV ADOLF HECKERT, a subject of the German Emperor, residing at Munich, in the Empire of Germany, have invented certain new and useful Improvements in Gas-Retorts, of which the following is a full, clear, and exact description.

For the purpose of generating water-gas steam has been introduced into a retort 10 through an iron pipe lying on the bottom of the retort. As, however, such an iron pipe burns after it has been in use for a short time, it was attempted to construct a steam-duct in the wall of the retort, but without success, 15 because the inlets from the duct into the retort were perpetually being stopped up by the coal-dust and products of distillation. If steam is not constantly issuing from these inlets—that is to say, if the admission is only 20 periodical—during the intervals of no admission of steam the particles of coal or the like lying in front of or around the inlets are soon converted into graphite and completely 25 cut off the steam-duct from the interior of the retort.

The present invention eliminates all these objections and also involves the particular advantage that the retort and the steam or gas duct or ducts are independent of each other 30 in respect of their life.

These objects are achieved by arranging the duct for introducing gas or steam into the retort as a piece separate from the wall of the retort and not lying within the wall. Thus 35 the duct is independent of the retort and is made of a refractory material like fire-clay.

In the accompanying drawings one form of the invention is illustrated.

Figure 1 is a vertical cross-section of a retort having two ducts made according to the invention. Fig. 2 is a part longitudinal vertical section of the retort. Fig. 3 is a perspective view of one of the sections made of refractory material whereof the ducts for 45 the steam or gas that is to be introduced into the retort are constructed.

The retort *a* has a cross-section such that the bottom angles *b* and *c* are shaped to receive interchangeable duct-sections *d* which 50 when laid end to end constitute the gas or steam duct. These sections have outlet-openings *e* of suitable form and size, which afford communication between the passage through the section and the interior of the 55 retort.

In order that during the charging or dis-

charging of the retort particles of coal or coke may not enter the openings *e* and stop them up, the latter are inclined, preferably at a sharp angle, toward the bottom of the retort. Moreover, in the form here illustrated the openings *e* are beneath a projecting part *h*, whereby when the retort is being filled the openings are not choked.

The cross-section of the steam or gas duct section *d* is such that it fits the inner contour of the angles *b* and *c* and the bottom *g* of the retort. On the bottom *g* is a longitudinal rib *i*, against which the lower edge of the vertical side *k* of the section *d* rests. Overhanging the bottom angles *b* and *c* of the retort are longitudinal ribs on the sides of the retort with which a correspondingly-shaped longitudinal shoulder *n* on the upper part of the section *d* engages when the section is pushed 75 into the retort from the front thereof. In this manner tipping forward a lateral shift of the section is prevented.

Inasmuch as the steam or gas duct sections herein described are made removable, the repair of one part need not disturb the other parts. This advantage is enhanced by the fact that the ducts are subdivided, so that when a section is damaged only that particular section need be changed for a new 85 one.

Obviously this invention is not limited to the particular shape and cross-section of the retort and duct-sections shown on the drawings. Moreover, instead of the two ducts 90 shown in the retort there may be several or only one.

This invention is applicable with equal advantage to horizontal and inclined retorts.

Having now particularly described and ascertained the nature of my said invention and the best means I know of carrying the same into effect, I claim—

1. In combination, a retort, interchangeable tubular sections of refractory material together forming an independent duct, removably combined with the retort, and passages leading from the interior of said duct into the interior of the retort.

2. In combination, a retort, an independent duct of refractory material, removably combined therewith, so as to form a continuation thereof in cross-section, downwardly inclined passages leading from the interior of the said duct into the interior of the retort, and a longitudinal projection on the said duct over the said passages.

3. In combination, a retort and interchangeable sections of refractory material together forming an independent duct, the said sections being removably combined 5 with the retort so as to form a continuation thereof in cross - section, downwardly - inclined passages leading from the interior of each section into the interior of the retort, and a longitudinal projection on each section 10 over the said passages.
4. In combination, a retort, a longitudinal rib on the bottom thereof, longitudinal ribs on the sides thereof overhanging the bottom angles thereof, duct-sections of refractory 15 material, a longitudinal shoulder on each sec-

tion adapted to engage the said longitudinal rib on the side of the retort, a vertical side to each section adapted to engage against the said longitudinal rib on the bottom of the retort, and downwardly-directed passages 20 leading from the interior of each section into the interior of the retort.

In testimony whereof I have hereunto affixed my signature in the presence of two witnesses.

GUSTAV ADOLF HECKERT.
